UNITED STATES PATENT OFFICE

1,925,623

SPACING MECHANISM

James L. Bernard, Beaver, and Frank K. McDanel, Ambridge, Pa.; Sophia L. Bernard executrix of said James L. Bernard, deceased

Application May 15, 1931. Serial No. 537,740

4 Claims. (Cl. 164—117)

This invention relates to spacing indicators for punching machines and the like, and, while not limited thereto, relates more particularly to spacing indicators for indicating the movement of a beam or other work-piece through the punch.

The object of this invention is to provide means for accurately locating the points to be punched in a work-piece while the work-piece is being moved through the punching machine.

Another object is to provide apparatus capable of accurate operation with any shaped beam or other work-piece.

In the drawings:

Figure 1 is a plan view of a punching machine having the indicating mechanism of this invention applied thereto.

Figure 2 is a side elevation thereof.

Figure 3 is an enlarged sectional elevation taken on the line III—III of Figure 1.

Figure 4 is a plan view of a punching machine having a modified form of indicating mechanism applied thereto.

Figure 5 is a partial side elevation thereof.

Figure 6 is a fragmentary sectional plan showing the guide wheel and tape-operated power sprocket for the indicator of Figures 4 and 5.

Figure 7 is an enlarged end elevation showing the tape storage drum and counterweight return.

Figure 8 is an enlarged sectional elevation through the indicator mechanism of Figures 4 and 5.

Referring more particularly to the drawings, the numeral 2 designates a punching machine of any usual and well known construction. A run-out table 3 is provided on the exit or run-out side of the punch and is provided with the usual carriage 4 having flanged wheels 5 and plain wheels 6 mounted to travel on the table when the carriage is propelled therealong.

A rack 7 is mounted on the table 3 and a shaft 8 is journaled in suitable bearings in the table 3 and provided with a pinion 9 which is meshed with the rack 7. The outer end of the shaft 8 is provided with a hand-wheel 10 by which the shaft may be rotated to cause the pinion to travel along the rack 7 and propel the carriage 4 lengthwise of the table 3.

The carriage 4 is provided with gripper jaws 12 adapted to grip the forward end of the work-piece or beam to pull or convey it through the punching machine when the carriage is moved or propelled along the table 3.

A clock-type indicating mechanism B is mounted on the carriage and is adapted to indicate the amount of movement of the carriage and work-

piece along the table 3. The mechanism B comprises a supporting structure 14 having a tubular standard 15. A dial 16 is secured on the structure 14 and bears two series of indicia, one series representing feet and the other representing inches. A vertical shaft 17 is journaled in the standard 15 and carries a bevel pinion 18 on its lower end which is meshed with a bevel pinion 19 on the inner end of the shaft 8.

The upper end of the shaft 17 carries a bevel pinion 20 which is meshed with a bevel pinion 21 carried by a tubular shaft 22 journaled in a bracket 23 on the structure 14 and in the dial 16. The shaft 22 projects through the dial and carries an indicating hand 24 adapted to cooperate with one of the series of indicia to indicate the inches of travel of the carriage and work.

A second shaft 25 is journaled in the shaft 22 and in a bracket 26 and projects beyond the forward end of the shaft 22. An indicating hand 27 is mounted on the projecting forward end of the shaft 25 and is adapted to cooperate with the second series of indicia to indicate the feet of travel of the carriage and work.

The shaft 25 is adapted to be driven from the shaft 22 by means of a pinion 28 carried by the shaft 22 and meshed with a gear 29 on a shaft 30 journaled in the brackets 23 and 26 and carrying a pinion 31 which is meshed with a gear 32 carried by the shaft 25.

The respective gearing connecting the shafts 22 and 25 with the vertical shaft 17 and the bevel gears or pinions 18 and 19 are so proportioned and designed that the indicating hands of the device will move around the dial 16 at the correct speed to accurately indicate the feet and inches of movement of the carriage and work-piece along the table 3.

The vertical shaft 17 is provided with a slip coupling 17^a to permit resetting of the hands 24 and 27 when necessary.

The rotation of the shaft 8 by the hand-wheel 10 to propel the carriage along the table 3 causes a simultaneous operation of the indicating mechanism and permits the operator to readily position the work-piece under the punch.

A plate or board 34 is mounted adjacent the indicator mechanism and is provided with clips 35 for holding a sketch or drawing showing the layout of the work-piece to be punched.

In Figures 4 to 8 we have shown a modified form of the invention in which the indicating mechanism is mounted on punching machine housing rather than on the carriage 4.

In this construction the clock-type indicating

mechanism B is mounted on the side of the punching machine housing nearest the carriage 4 instead of on the carriage and a slightly different operating means is provided for the indicating mechanism drive means.

- The indicating mechanism B comprises a supporting structure 36 on which is mounted a dial 37 bearing two series of indicia, one series representing feet and the other representing inches. 10 A vertical shaft 38 is journaled in the supporting structure 36 and carries a pinion 39 on its lower end which is meshed with a bevel pinion 40 on a shaft 41 which extends across the rear of the punching machine to the entering side 15 thereof.

The upper end of the shaft 38 carries a bevel pinion 42 which is meshed with a bevel pinion 43 carried by a tubular shaft 44 journaled in a bracket 45 on the structure 36 and in the dial 20 37. The shaft 44 projects through the dial and carries an indicating hand 46 adapted to cooperate with one of the series of indicia to indicate the inches of travel of the carriage and work.

A second shaft 47 is journaled in the shaft 25 44 and in a bracket 48 and projects beyond the forward end of the shaft 44. An indicating hand 49 is mounted on the projecting forward end of the shaft 47 and is adapted to cooperate with the second series of indicia to indicate the feet 30 of travel of the carriage and work.

The shaft 47 is adapted to be driven from the shaft 44 by means of a pinion 50 carried by the shaft 44 and meshed with a gear 51 on a shaft 52 journaled in the brackets 45 and 48 and carrying a pinion 53 which is meshed with a gear 35 54 on the shaft 47.

The shaft 41 is the drive-shaft for the indicating mechanism of this construction and receives its power from a shaft 55 journaled in 40 brackets 56 on the entering side of the punching machine 2 and connected to the shaft 41 by bevel pinions 57 and 58.

A bracket-plate 59 is mounted on the entering 45 side of the punching machine 2 and a shaft 60 is journaled thereon and carries drums 61 and 62 on its opposite ends. The drum 61 serves as a storage drum for a perforated driving tape 63 which is trained down over and meshed with the teeth of a sprocket wheel 64 carried by the shaft 55. A guide wheel 65 is provided for holding the 50 tape 63 in contact with the sprocket 64.

The free end of the tape 63 is provided with a clip 63^a adapted to be engaged with the forward end of the beam or work-piece being punched so that as the work-piece is advanced the tape will be pulled from the drum 61 and over the sprocket 64, thereby rotating the sprocket and shaft 55 to drive the indicating mechanism simultaneously with the movement of the carriage 4 and the work-piece.

The gearing for driving the indicating hands is so proportioned and designed that the hands will accurately indicate the travel of the work-piece and carriage in feet and inches.

The drum 62 serves as a storage drum for a counterweight cable 66 which is trained over a double block and fall 67 carried by a bracket 68. The block and fall 67 carries a counterweight 69.

In operation, when the tape 63 is pulled from the drum 61, the shaft 60 will be rotated to take up the cable 66 and raise the counterweight 69, and when said tape is released from the work-piece the counterweight 69 will exert a pull through the block and fall 67 and cable 66 so as to reversely rotate the drum 62, shaft 60 and

drum 61, thereby taking up the tape. This reverse movement of the tape 63 will reverse the direction of movement of the indicating hands and return said hand to zero.

The vertical shaft 38 of the indicating mechanism has a slip coupling 70 to permit resetting the indicating mechanism if, for any reason, the hands do not point to zero when starting the operation.

While we have shown and described certain specific embodiments of our invention it will be understood that we do not wish to be limited thereto since various modifications may be made without departing from the scope thereof, as defined in the appended claims.

We claim:

1. In a punching apparatus for punching beams, a carriage for conveying the beams through said punching apparatus, a clock-type indicator for indicating the movement of said carriage, said indicator having one hand indicating the movement of said carriage in feet and another hand indicating said movement in inches and fractions of an inch, suitable drive mechanism for said hands, means for propelling said carriage, and means for operating said indicator hand drive mechanism simultaneously with the movement of said carriage, said last named means including a sprocket carried by said indicator drive mechanism, and a flexible drive element meshed with said sprocket and adapted to be connected with the forward end of the beam being conveyed by said carriage whereby movement of said carriage and beam will be communicated through said flexible element and said sprocket to said indicator drive.

2. In a punching apparatus for punching beams, a carriage for conveying the beams through said punching apparatus, a clock-type indicator for indicating the movement of said carriage, said indicator having one hand indicating the movement of said carriage in feet and another hand indicating said movement in inches and fractions of an inch, suitable drive mechanism for said hands, means for propelling said carriage, and means for operating said indicator hand drive mechanism simultaneously with the movement of said carriage, said last named means including a sprocket carried by said indicator drive mechanism, a flexible drive element meshed with said sprocket and adapted to be connected with the forward end of the beam being conveyed by said carriage whereby movement of said carriage and beam will be communicated through said flexible element and said sprocket to said indicator drive mechanism, and means for retracting said flexible element.

3. The combination with a movable carriage, of a clock-type indicator for indicating the movement of said carriage, said indicator having one hand indicating the movement of said carriage in feet and another hand indicating said movement in inches and fractions of an inch, suitable drive mechanism for rotating said hand, and means for operating said drive mechanism, said means comprising a sprocket, a flexible tape member provided with spaced perforations and meshed with said sprocket, a drum on which said tape is normally coiled, said tape being adapted to be pulled over said sprocket when said carriage is moved forward, and means for retracting said tape.

4. The combination with a movable carriage, of a clock-type indicator for indicating the movement of said carriage, said indicator having one hand indicating the movement of said carriage in

feet and another hand indicating said movement in inches and fractions of an inch, suitable drive mechanism for rotating said hands, and means for operating said drive mechanism, said means comprising a sprocket, a flexible tape member provided with spaced perforations and meshed with said sprocket, a drum on which said tape is nor-

mally coiled, said tape being adapted to be pulled over said sprocket when said carriage is moved forward, and counterweight means for revolving said drum in the reverse direction to retract said tape.
